GAS MANUFACTURING APPARATUS

Gerald J. Nordmeyer, Oak Park, Ill., assignor to
The Koppers Company of Delaware, a corpora-
tion of Delaware

Application October 9, 1929. Serial No. 398,340

2 Claims. (Cl. 48—79)

This invention relates to gas manufacturing apparatus and particularly to carburetters for carburetted water-gas sets. More particularly it relates to the construction by means of which 5 the gas offtake pipe from the generator is connected to the carburetter to form the inlet for the same.

In carburetters as previously constructed, the connection from the generator to the carburetter is generally arranged at right angles to the shell of the carburetter and the flow of blue water gas from the generator enters the carburetter through the inlet piping in such a direction that most of the oil admitted by the centrally located oil spray is carried to the opposite 15 side of the carburetter and impinges on the checkerbrick and the part of the wall furthest removed from the gas inlet.

As a result, a large portion of the vaporizing 20 and cracking of oil occurs on one side of the carburetter. More carbon is deposited on the wall and checkerbrick in this portion of the carburetter than is deposited on those sections nearer to the gas inlet. This condition necessitates 25 recheckerering of the entire carburetter before the life of all of the checkerbrick has been fully utilized.

The present invention comprises the feature of connecting the gas inlet to the carburetter in 30 such a manner that it is tangential to the inner periphery of the carburetter.

An object of the invention is to improve the efficiency of the cracking of the gas oil by securing a more even distribution of the oil to the carburetter than has heretofore been possible in 35 previous types.

Another object is to prolong the useful life of the carburetter checkerering by preventing the undesired deposition of carbon on the checkerbrick 40 from being localized at one side of the carburetter.

Another object is to secure a more even heat distribution in the checkerbrick of the carburetter during the blasting period by imparting a 45 swirling motion to the heating gases thereby effecting a more complete mixing of gas and air for combustion and assuring more intimate contact between the gases and the checkerbrick.

My invention also includes the feature of arranging the connection from the carburetter to the superheater tangent to the walls of the superheater. When applied to a gas making set equipped for the backrun process this connection 50 may also be arranged tangent in the reverse direction to the carburetter whereby the backrun

steam enters the carburetter from the superheater in a tangential direction.

In the drawings,

Figure 1 is a plan view of a carburetted water-gas set provided with the improved inlet for the carburetter;

Fig. 2 is an elevation of the carburetted water-gas set shown in Fig. 1, partially in cross-section on the line II—II of Fig. 1;

Fig. 3 is a reduced plan view of a carburetted water-gas set having a modified form of carburetter inlet;

Fig. 4 is a plan view of a backrun set provided with improved inlets for the carburetter and superheater; and

Fig. 5 is an elevation of the set shown in Fig. 4.

The carburetted water-gas set shown in Figs. 1 and 2 comprises a water gas generator 1 that is connected to a carburetter 2 by means of a top gas offtake pipe 3 and an inlet 4 which is tangential to the inner periphery of the carburetter. The carburetter is provided with an oil spray 5. Air is supplied to the lower part of the generator through a main blast pipe 6, a primary blast valve 7 and a downrun pipe 8.

Secondary air is admitted to the carburetter through a secondary blast pipe 10 and a secondary blast valve 11. The pipe 10 joins a pipe 12 immediately below the inlet 4. The pipe 3 ends in a dust collector 14. Steam for the uprun is supplied by an inlet 15. Downrun steam enters the generator through connection 16.

During the downrun portion of the cycle, gas can pass from the bottom of the generator to the carburetter through downrun pipe 8 and the connecting pipe 12 if a hot valve 18 is in the right position. The hot valve 18 is a reversing valve which intersects both pipes 3 and 12 and always closes the one or the other of the two pipes. The pipe 12 joins the top gas offtake pipe 3 immediately under the inlet 4.

The improved type of carburetter shown in Fig. 3 is a modification of that shown in Figs. 1 and 2 and differs therefrom in having two inlet branches 22 and 23 leading from the top gas offtake pipe 3 tangentially to different points on the inner periphery of the carburetter 2. This design is used when a greater swirling action than that produced by the single tangential inlet is desired. The carburetted water-gas set shown in Fig. 3 includes a superheater 24.

In Figs. 4 and 5 my improved type of inlet is applied to the carburetter and also to the superheater of a carburetted water-gas set equipped for the "back-run" process. In this type of set,

the down-run steam is introduced through an inlet 26 at the top of the superheater 24 and passed downward through the superheater, upward through the carburetter 2 and downward 5 through the generator 1 whence it passes through a back-run pipe 27 to a tar batter or wash box 28. There is no hot valve for offtake pipe 3, such as valve 18 of Fig. 1, and the pipe 3 remains open throughout the cycle. The pipe 10 3 is tangent to the inner periphery of the carburetter.

The connection 30 for conducting gas from the carburetter 2 to the superheater 24 is tangent to the inner periphery of the superheater. The 15 tangential arrangement of the connecting pipe 30 prevents the depositing of dust in a single portion of the superheater 24 and otherwise results in greater uniformity of heat transfer throughout the checkerbrick work of the super- 20 heater.

The pipe 30 does not enter the carburetter 2 at right angles but is tangent thereto and this arrangement results in a better absorption of heat from the carburetter bricks during the back- 25 run.

As will be apparent from the drawings and more particularly Figs. 4 and 5 thereof, the connections 3 and 30 are not only arranged tangentially with respect to the carburetter 2 but oppositely, that is to say, that the direction of rotation induced by the discharge of forwardrun gases from the connection 3 into the carburetter 2 is the same as the direction of rotation induced by the discharge of backrun gases from the connection 30 into the carburetter 2. Conversely, either one of the connections 3 or 30 is adapted to discharge gases from the carburetter 2 in a direction opposite or counter to the direction of the rotation induced by gases entering the carburetter 2 through the other.

The superheater 24 is provided with a stack valve 32, a pipe 33 to the tar batter 28, the latter being connected to a gas main 34. The downrun steam pipe 26 is connected to the stack 35 leading from the superheater to the stack valve for securing good distribution of steam at the top of the superheater.

In the operation of the back-run set, the time available for injecting the oil is very short, being limited to the first uprun period. If oil were supplied during the back-run period, excessive cracking of the oil gas formed would result, due to its passage through the fuel bed in generator 1. The carburetter inlet of my invention is especially advantageous on a back-run set, since, because of the swirling motion of the gases, more intimate contact between the oil and the cracking surfaces is obtained, notwithstanding the higher rate of the oil input.

Either a single tangential inlet to the carburetter or a plurality of tangential inlets may be used with the back-run set. The improved type of carburetter requires no more head room and is little if any more expensive to install than the present type of carburetter. Existing carburetters can be readily modified to incorporate the

new improvement through minor changes and at small cost.

In operation the tangential inlet of the improved type of carburetter introduces both the blast gas and the water gas in such manner as to produce a turbulent flow. There is much more agitation of the gases and a more even distribution of heat during the passage of blast gas than occurs in the present type of carburetter.

The tangential direction of the inlet produces a swirling motion about the periphery of the carburetter and the centrally located oil spray directs the flow of oil into the center of the vortex of the whirling gases so that the oil spray is quite uniformly distributed through the fire bricks of the carburetter and utilizes the heat of all of them, thereby improving the efficiency of the vaporization and cracking of the oil.

The formation of carbon deposits on the brick-work of the carburetter is prevented altogether in most instances and is always kept from depositing in large amounts and kept from depositing on a limited portion of the checkerbrick work.

I claim as my invention:

1. In an apparatus for manufacturing carburetted water gas, the combination of generator and carburetter elements, a gas inlet pipe connecting said elements for admitting gas from the generator into the upper portion of the carburetter, said inlet pipe being disposed tangentially to the inner periphery of the carburetter, and a gas outlet pipe connection communicating with the lower portion of said carburetter and disposed substantially tangential to the inner periphery thereof, whereby gases from said generator are passed downwardly with a swirling motion through said carburetter from top to bottom thereof and thence outwardly therefrom, to obtain uniformity of enrichment of the gases in the carburetter and to insure a more even and balanced contact of said gases with the internal checkerbrick of the carburetter.

2. In an apparatus for manufacturing carburetted water gas, the combination of generator, carburetter and superheater elements, a gas inlet pipe for conducting gas from the generator into the upper portion of the carburetter, said inlet pipe being disposed tangentially to the inner periphery of the carburetter, a gas conduit connecting the lower portion of the carburetter with the lower portion of the superheater and disposed tangentially with respect to the inner peripheries of said elements, whereby gases from said generator are passed downwardly with a swirling motion through said carburetter from top to bottom thereof and thence tangentially into said superheater with a swirling motion and upwardly therethrough, whereby to obtain uniformity of enrichment of the gases in the carburetter and to insure a more even and balanced contact of said gases with the internal checkerbrick of the carburetter and superheater and to guard against localization of carbon deposits in the checkerbrick of said elements.

GERALD J. NORDMEYER. 140
